W. S. WARNOCK.
PRINTER'S REGISTERING DEVICE.
APPLICATION FILED MAR. 26, 1906.

1,007,164.

Patented Oct. 31, 1911.

UNITED STATES PATENT OFFICE.

WALLACE S. WARNOCK, OF CHICAGO, ILLINOIS.

PRINTER'S REGISTERING DEVICE.

1,007,164.

Specification of Letters Patent. Patented Oct. 31, 1911.

Application filed March 26, 1906. Serial No. 308,121.

To all whom it may concern:

Be it known that I, WALLACE S. WARNOCK, a citizen of the United States, residing at Chicago, in the county of Cook and State of Illinois, have invented a certain new and useful Improvement in Printers' Registering Devices, of which the following is a full, clear, concise, and exact description, reference being had to the accompanying drawings, forming a part of this specification.

My invention relates to registering devices for printers' use, and has several objects and may have different embodiments. It is old to form a printer's block provided with a movable clamp, a fixed rod extending through an extension of said clamp, and an adjusting device supported on said rod, the clamp being provided with means for retaining the adjusting device, whereby the adjusting device may adjust the clamp in either direction and travel with the same. In order that the adjusting device may be supported on the rod, a block forming a component part of the structure has to be provided, upon which said rod is mounted.

In practicing my present invention, I do not support the adjusting device on a fixed gear element, but rather I support said gear element upon the clamp and support the adjusting device on the clamp also, instead of on said gear element, by which novel construction I may, if desired, totally eliminate any easing or block, although in some types of devices it may be desirable to employ such block, in which event the gear element carried by each clamp need not be fastened to the block, for, as stated, the clamp carries said gear element and adjusting device. In the preferred embodiment of the invention, the block structure is eliminated and each registering device, therefore, includes a clamp, an adjusting device, and an exterior gear element, both carried by said clamp, in combination with means whereby the first aforesaid gear element is adapted to be maintained in a stationary position, so that the balance of the gear mechanism may coöperate therewith, in order to effect the operation of the clamp.

The adjusting device desirably, though not necessarily, includes a plurality of gear elements, preferably two in number, one of which gear elements is a worm shaft having a vertical axis of rotation, the remaining gear element being a worm wheel in

engagement with said worm shaft, access being had to the worm shaft by means of a suitable tool through the hook portion of the clamp. The gear element that is carried by the clamp is desirably, though not necessarily, in the form of a rack bar, and there is preferably provided upon the same shaft that carries the worm wheel a pinion that engages the said rack. In the preferred embodiment of the invention, the rack teeth are in duplicated sets and there are provided two pinions, one for each set of rack teeth. The means that I preferably employ for maintaining said exterior gear element, the rack structure, in a stationary position resides in a pin provided upon the bottom of said rack structure adapted to engage any of a number of pin holes provided in grooves formed in the foundation plate. The foundation plate is desirably, though not necessarily, composed of a plurality of separably and individually constructed blocks, each block being grooved, these blocks, when properly assembled, having the grooves therein properly alined, so that slots are established upon the foundation plate thus compositely formed of the blocks. The slots in the individual blocks are desirably diagonally disposed, though I do not wish to be limited to this arrangement. By this preferred construction, I am enabled, first, to roughly approximate the position of the clamp or register hook with respect to the plate or material it is to hold, and thereafter accurately to adjust the register hook so that the plate or other material may be nicely adjusted in position. In this preferred embodiment of the invention, the pin constitutes the means for determining the position of the exterior gear element, but where a block structure is employed as a component part of each device, said block structure preferably constitutes the means for positioning said exterior gear element. Where the pin or equivalent means is employed for holding the exterior gear element, I desirably employ means in addition thereto for preventing the register hook from rising from the slot in the foundation plate of the press, to which end I make the base of the clamp, that portion which is adapted to extend into the foundation groove, collapsible or contractible in size, so that its size may be decreased as it is passed into the slot and thereafter be permitted to expand, so that the structure

will be prevented from rising. The base of the clamp is preferably made contractible or collapsible by having the same formed in part of a spring member, which spring member is desirably symmetrically formed, a symmetrical part of the spring margining each longitudinal edge of the balance of the base structure, these margining portions of the spring member being desirably united by two U-shaped portions formed integrally therewith and received in semi-circular recesses in the clamp structure. The spring member of the clamp base has a tendency to move outwardly away from the balance of the base, whereby the aforesaid marginal portions of the spring member are adapted to underlie overhanging lips margining the grooves in the plate foundation.

My invention comprises, in its preferred embodiment, a spacer for a grooved foundation or bed for printing plates comprising a body portion adapted to be passed down at any place into a groove, a transverse jaw coming above the foundation and adapted to come between the printing plates and engage adjacent edges of two plates, and devices, preferably spring actuated, separate from and mounted upon said body portion and coming directly beneath the printing plate engaged, at each side of the jaw and adapted to engage, preferably automatically, said groove to hold the spacer to the bed and prevent accidental separation.

I will explain my invention more fully by reference to the accompanying drawing, illustrating the preferred embodiments thereof, in which—

Figure 1 indicates a number of separable blocks of the kind employed compositely to form a plate foundation, the register hook of my invention being shown in position. Fig. 2 is a sectional view on an enlarged scale on line 2 of Fig. 1. Fig. 3 is a sectional view on line 3 of Fig. 2. Fig. 4 is a plan view of a modified hook structure. Fig. 5 is a sectional view on line 5 of Fig. 4. Fig. 6 is a perspective view of the spring mechanism.

Like parts are indicated by similar characters of reference throughout the different figures.

The plate foundation may be of any suitable construction, and, if desired, have grooves 6 extending across the same, these grooves preferably being diagonally disposed. If preferred, the plate foundation may be composed of a plurality of separable blocks 7 in which these grooves are diagonally formed, the blocks, when properly assembled, having the grooves therein suitably aligned to establish the continuations thereof over the foundation or base plate. The grooves 6 that are not occupied by register hook structures may be filled with filler blocks 8, so that a level surface may be afforded for the plate. The exterior gear ele-

ment 9 may be in the form of a rack bar longitudinally margined by rows of rack teeth, which rack bar may be provided with a pin 10 adapted to engage any of several holes 11 in the plate foundation, to approximate the position of the register hook structure with respect to the plate, as 12, that is to be clamped in position. The pin 10 stationarily holds the rack bar and affords a purchase for the gear element 9, so that the clamp structure 13 may travel thereupon to bring the clamping jaw 14 into engagement with the plate, as 12.

The clamping jaw 14 comes above the foundation formed by the blocks 7 and is recessed as indicated most clearly in Fig. 2, so that each side of the jaw may engage a printing plate, one printing plate 12 being shown in engagement with the transverse jaw 14. The transverse jaw, by its construction, is adapted to come between the printing plates and engage adjacent edges of two plates.

As I have preferably provided a rack bar and two rows of rack teeth thereon, I provide pinions 15 upon the base of the clamp, which pinions are fixed upon the square portion of the shaft 16, which square portion also fixedly carries a worm wheel 17 meshing with a vertically disposed worm shaft 18 provided with a vertical key receiving socket, as indicated in Fig. 2. The shaft 16 is desirably journaled in two disks 19 that are fixed in the sides of the base of the clamp, each preferably by a drying fit. The bottoms of these sides of the clamp base are inturned, as indicated most clearly in Fig. 3, whereby the gear element 9 is carried by the clamp base, while at the same time longitudinal movement of said gear element with respect to said base is permitted. When the worm shaft 18 is rotated, the worm wheel 17 is rotated, and as the pinions 15 rotate with said worm wheel, the clamp is moved back and forth upon the exterior gear element 9.

The clamping jaw 14, extending transversely of the groove into any part of which the spacer of my invention may be inserted, has a peripherally grooved base which is held in a normal plane of movement by means of pins 20. This permits the said clamping jaw to be rotated to suit the position of the plate 12. The worm shaft 18 has its upper end projected into a recess provided in said peripherally grooved base, the upper end of said worm shaft having abutment against a horizontal face of said base, while the lower end of said shaft is held in position by means of an adjusting screw or bearing 21. By rotation of this adjusting screw 21, any vertical lost motion or end play of the worm shaft 18 may be prevented. It will be understood that the clamping jaw 14 is provided with an aper-

ture in line with the key receiving socket of said worm shaft, so that a key may be freely passed through said aperture and into engagement with the key socket of said shaft.

5 In order that the clamp may not be vertically displaced, I include as a component part of the base of said clamp a spring member 22 having two yokes 23 of a form illustrated clearly in Figs. 2 and 3, said spring member being preferably formed of strip spring metal and under such tension that the upper longitudinal marginal portions of said spring member tend to assume positions removed from the balance of the clamp base 10 to underlie overhanging lips 24.

Where it is desired to employ blocks instead of some such device as the pins 10, for defining the positions of the rack bars 9, I may use some such construction as that 15 indicated in Figs. 4 and 5, which disclose clamping structures preferably identical with the clamping structure shown in Figs. 1 to 3, inclusive, but wherein the gear elements 9 may be considerably shortened. 20 These blocks may form separable parts of the plate foundation and the end walls thereof may constitute abutments between which the gear element 9 is disposed, and which preferably serve to prevent any travel 25 of said gear element. The sides of the block may have tongue and groove engagement 30 with the base of the clamp to prevent the clamp from rising with respect to the block, as indicated in Fig. 5.

35 It will be observed, by reference to Figs. 4 and 5, that the device of my invention enables me to employ a very narrow block or body portion 25 for the register hook, said block or body portion being adapted to be 40 passed down at any place into the groove. I have produced blocks two and two-thirds picas wide, but the width of these blocks may still be further reduced. I am not aware that blocks of this narrow width 45 carrying register hook structures have ever hitherto been produced.

The spring member 22 has two long portions that are adapted directly to engage beneath the overhanging lips 24, these long 50 portions constituting devices separate from and mounted upon said body portion at each side of the jaw and adapted automatically to engage the groove to hold the spacer to the bed and prevent accidental separation.

55 It will be seen that in the preferred embodiment of my invention I have provided a spacer for a grooved foundation or bed for printing plates comprising a body portion adapted to be passed down at any place into a groove, a transverse jaw coming above the foundation and adapted to come beneath the printing plates and engage adjacent edges of two plates, and devices, preferably spring actuated, separate from and

mounted upon said body portion and coming directly beneath the printing plate engaged, at each side of the jaw and adapted to engage, preferably automatically, said groove to hold the spacer to the bed and prevent 70 accidental separation.

Certain features of construction herein shown are claimed in my co-pending applications Serial No. 231,362, filed November 4, 1904, plate holders, and Serial No. 283,651, 75 filed October 20, 1905, printers' registering devices.

While I have herein shown and particularly described the preferred embodiments of the invention, it is obvious that changes 80 may readily be made without departing from the spirit of the invention, and I do not, therefore, wish to be limited to the precise constructions shown, but,

Having thus described my invention, I 85 claim as new and desire to secure by Letters-Patent:

1. A device of the class described including a pivotally mounted jaw having a peripherally grooved base, a device in said groove for limiting the said jaw to a single plane of rotation, and an operating shaft 90 located below the jaw, said jaw being apertured to permit of access of an operating tool therethrough to the said shaft. 95

2. A device of the class described including a jaw with its base, gearing carried by the base, said base being contractible and automatically expansible, and an external gear element coöperating with the aforesaid gearing and with respect to which the jaw structure may travel. 100

3. A device of the class described including a jaw with its base, gearing carried by the base, said base being contractible and 105 expansible, and an external gear element coöperating with the aforesaid gearing and with respect to which the jaw structure may travel, said contractible and expansible base including a spring member. 110

4. A device of the class described including a jaw with its base, and gearing carried by the base, said base being contractible and expansible, said contractible and expansible base including a spring member formed of 115 strip spring metal.

5. A device of the class described including a jaw with its base, gearing carried by the base, said base being contractible and expansible, and an external gear element coöperating with the aforesaid gearing and with respect to which the jaw structure may travel, said contractible and expansible base including a spring member formed of strip 120 metal. 125

6. A device of the class described including a jaw with its base, gearing carried by the base, said base being contractible and automatically expansible, an external gear element coöperating with the aforesaid 130

gearing and with respect to which the jaw structure may travel, and means coöperating with said external gear element whereby the latter is held stationary.

- 5 7. A device of the class described including a jaw with its base, gearing carried by the base, said base being contractible and expansible, an external gear element coöperating with the aforesaid gearing and with 10 respect to which the jaw structure may travel, said contractible and expansible base including a spring member, and means coöperating with said external gear element whereby the latter is held stationary.
- 15 8. A device of the class described including a jaw with its base, gearing carried by the base, said base being contractible and expansible, an external gear element coöperating with the aforesaid gearing and with 20 respect to which the jaw structure may travel, said contractible and expansible base including a spring member formed of strip spring metal, and means coöperating with said external gear element whereby the latter is held stationary.

25 9. The combination with a grooved foundation or bed, of a printing plate holder whose base is adapted to be passed down into a groove in said bed, a traveling plate-holding jaw coming above the foundation, automatically operated mechanism for holding the jaw in relation to the bed, a gear element stationarily held in said groove, and means for propelling the plate holder 30 in both directions by engagement with said gear element.

40 10. The combination with a grooved foundation or bed, of a printing plate holder whose base is adapted to be passed down into a groove in said bed, a traveling plate-holding jaw coming above the foundation, spring mechanism for holding the jaw in relation to the bed, a gear element 45 stationarily held in said groove, and means for propelling the plate holder in both directions by engagement with said gear element.

50 11. The combination with a grooved foundation or bed, of a printing plate holder whose base is adapted to be passed down into a groove in said bed, a traveling plate-holding jaw coming above the foundation, mechanism for holding the jaw in relation to the bed, a double rack stationarily 55 held in said groove, and means for propelling the plate holder in both directions, said means including two pinions carried upon opposite sides of the base of the jaw and in engagement with the double rack.

60 12. The combination with a grooved foundation or bed, of a printing plate holder whose base is adapted to be passed down into a groove in said bed, a traveling plate-holding jaw coming above the foundation, automatically operated mechanism

for holding the jaw in relation to the bed, a double rack stationarily held in said groove, and means for propelling the plate holder in both directions, said means including two pinions carried upon opposite sides of the base of the jaw and in engagement with the double rack.

65 13. The combination with a grooved foundation or bed, of a printing plate holder whose base is adapted to be passed down into a groove in said bed, a traveling plate-holding jaw coming above the foundation, automatically operated spring mechanism for holding the jaw in relation to the bed, a double rack stationarily held in said groove, and means for propelling the plate holder in both directions, said means including two pinions carried upon opposite sides of the base of the jaw and in engagement with the double rack.

70 14. The combination with a grooved foundation or bed, of a printing plate holder whose base is adapted to slide in a groove in said bed, a traveling jaw coming above the foundation, a double rack stationarily held in said groove, and means for propelling the plate holder in both directions, said means including two pinions carried upon opposite sides of the base of the jaw and in engagement with the double rack.

75 15. The combination with a grooved foundation or bed, of a printing plate holder whose base is adapted to be passed down into the groove in said bed, a plate-holding jaw extending across the containing groove and coming above the foundation, automatically operated mechanism for holding the jaw in relation to the bed, and engaging means stationary with respect to the bed and along which the printing plate holder may be moved and thereby be held in differing positions along the groove.

80 16. The combination with a grooved foundation or bed, of a printing plate holder whose base is adapted to be passed down into the groove in said bed, a plate-holding jaw extending across the containing groove and coming above the foundation, spring mechanism for holding the jaw in relation to the bed, and engaging means stationary with respect to the bed and along which the printing plate holder may be moved and thereby be held in differing positions along the groove.

85 17. The combination with a grooved foundation or bed, of a printing plate holder including a jaw disposed across its associate groove and coming above the bed, automatically expansible mechanism adapted to be passed down into said groove and serving to hold the jaw in relation to the bed, and engaging means stationary with respect to the bed and along which the printing plate holder may be moved and thereby be held in differing positions along the groove.

18. The combination with a grooved foundation or bed, of a printing plate holder including a jaw disposed across its associate groove and coming above the bed, automatically operated mechanism adapted to be passed down into said groove and serving to hold the jaw in relation to the bed, and engaging means stationary with respect to the bed and along which the printing plate holder may be moved and thereby be held in differing positions along the groove.
19. The combination with a grooved foundation or bed, of a printing plate holder including a jaw disposed across its associate groove and coming above the bed, spring mechanism adapted to be passed down into said groove and serving to hold the jaw in relation to the bed, and engaging means stationary with respect to the bed and along which the printing plate holder may be moved and thereby be held in differing positions along the groove.
20. The combination with a grooved foundation or bed, of a printing plate holder, a traveling plate-holding jaw coming above the foundation and extending across a groove in said bed, automatically expansible mechanism adapted to be passed down into said groove, for holding the jaw in relation to the bed, a gear element stationarily held in said groove, and means for propelling the plate holder in both directions by engagement with said gear element.
21. The combination with a grooved foundation or bed, of a printing plate holder, a traveling plate-holding jaw coming above the foundation and extending across a groove in said bed, automatically operated mechanism adapted to be passed down into said groove, for holding the jaw in relation to the bed, a gear element stationarily held in said groove, and means for propelling the plate holder in both directions by engagement with said gear element.
22. The combination with a grooved foundation or bed, of a printing plate holder, a traveling plate-holding jaw coming above the foundation and extending across a groove in said bed, spring mechanism adapted to be passed down into said groove, for holding the jaw in relation to the bed, a gear element stationarily held in said groove, and means for propelling the plate holder in both directions by engagement with said gear element.
23. The combination with a grooved foundation or bed, of a printing plate holder, a traveling plate-holding jaw coming above the foundation and extending across a groove in said bed, mechanism adapted to be passed down into said groove, for holding the jaw in relation to the bed, a double rack stationarily held in said groove, and means for propelling the plate holder in both directions, said means including two pinions carried upon opposite sides of the base and in engagement with the double rack.
24. The combination with a grooved foundation or bed, of a printing plate holder, a traveling plate-holding jaw coming above the foundation and extending across a groove in said bed, automatically operated mechanism adapted to be passed down into said groove, for holding the jaw in relation to the bed, a double rack stationarily held in said groove, and means for propelling the plate holder in both directions, said means including two pinions carried upon opposite sides of the base and in engagement with the double rack.
25. The combination with a grooved foundation or bed, of a printing plate holder, a traveling plate-holding jaw coming above the foundation and extending across a groove in said bed, automatically operated spring mechanism adapted to be passed down into said groove, for holding the jaw in relation to the bed, a double rack stationarily held in said groove, and means for propelling the plate holder in both directions, said means including two pinions carried upon opposite sides of the base and in engagement with the double rack.
26. The combination with a grooved foundation or bed, of a printing plate holder, a traveling jaw coming above the foundation and extending across a groove in said bed, a double rack stationarily held in said groove, and means for propelling the plate holder in both directions, said means including two pinions carried upon opposite sides of the base and in engagement with the double rack.

In witness whereof, I hereunto subscribe my name this 19th day of March A. D., 1906.

WALLACE S. WARNOCK.
